UNITED STATES PATENT OFFICE.

GUERINO RINALDI, OF WILMINGTON, DELAWARE.

TORPEDO-GUARD.

1,307,023.

Specification of Letters Patent. Patented June 17, 1919.

Application filed May 24, 1918. Serial No. 236,351.

To all whom it may concern:

Be it known that I, GUERINO RINALDI, a subject of the King of Italy, residing at Wilmington, in the county of New Castle and 5 State of Delaware, have invented new and useful Improvements in Torpedo-Guards, of which the following is a specification.

This invention relates to torpedo guards for marine vessels and it consists in the 10 novel features hereinafter described and claimed.

An object of the invention is to provide a guard of the character stated which is of 15 simple and durable structure and which may be easily and quickly applied to the plates of the hull of the vessel and easily and quickly removed from the same. The guard comprises a number of spikes each having points and globular portions which are disposed radially with respect to the side of the vessel when the said spikes are applied. These spikes are located at or in the vicinity of the waterline of the vessel, consequently an approaching torpedo will strike the spike 25 and will be set off by the point thus causing the explosion of the torpedo to take place exteriorly of the hull of the vessel.

The plates of the hull are provided with 30 threaded sockets adapted to receive the shanks of the spikes and when the shanks are removed, as for instance when the vessel is not in a danger zone the said sockets may be closed by suitable plugs inserted therein whereby the exterior surfaces of the plates 35 are made smooth consequently they will present no friction as the vessel passes through the water.

In the accompanying drawing:—

Figure 1 is a side elevation of a vessel with 40 the guard applied.

Fig. 2 is a fragmentary sectional view of the vessel showing a spike in position thereon.

Fig. 3 is a similar view showing a plug 45 inserted in the socket which receives the shank of the spike.

As illustrated in the accompanying drawing, the hull of the vessel is made up of 50 metallic plates 1 of usual form and pattern and these plates are provided with a number of threaded sockets 2. The guard comprises spikes 3 having threaded shanks 4 adapted

to engage the threads of the sockets 2 and the spikes 3 are each provided with a series of points 5 and the portions of the spikes between the said points are preferably formed globular in order to add sufficient metal to the spikes to make them strong and durable. Any number of points may be provided upon 55 each spike and they may be disposed in various directions with relation to the axis of the spike.

When the spikes are applied to the plates they stand out from the same and inasmuch as the sockets are located at or about the 60 waterline of the vessel the spikes are carried in the vicinity of the surface of the water. When the spikes are applied to the plates they completely close the sockets 2 and prevent the entrance of water into the sockets. 65 The sockets 2 do not pass completely through the plate and when the spikes are applied they are tapped in the plate in view of the fact that the shanks of the spikes do not pass 70 completely through the plate.

When the spikes are removed from the sockets the sockets may be closed by plugs 6.

It is obvious that when the vessel is passing through a danger zone the plugs may be removed from the sockets and the spikes 80 applied and in the event that a torpedo approaches the vessel and encounters the spikes the torpedo will be set off exteriorly of the hull of the vessel. When the vessel has passed through the danger zone the spikes 85 may be removed and the sockets may be closed by inserting the plugs 6 as described.

Having described the invention what is claimed is:—

A torpedo guard for marine vessels comprising in combination with the hull plates 90 said plates being provided with threaded sockets, spike members having threaded shanks engaged within said socket and terminating at their end points, a plurality of 95 radially extending points formed on each spike member in spaced relation to each other and to said first named points and an enlarged portion formed on each spike member adjacent the threaded shank and bearing 100 against the hull plate.

In testimony whereof I affix my signature.

GUERINO RINALDI.
